DESIGN FOR A SUN LAMP

Paul N. Cloutier, Decatur, Ill., assignor to Faries
Manufacturing Company, Decatur, Ill.

Application December 19, 1939, Serial No. 89,003

Term of patent 3½ years

To all whom it may concern:

Be it known that I, Paul N. Cloutier, a citizen of the United States and a resident of Decatur, in the county of Macon and State of Illinois, have invented a new, original, and ornamental Design for a Sun Lamp, of which the following is a specification, reference being had to the accompanying drawing, forming a part thereof.

Fig. 1 is a side elevational view of a sun lamp showing my new design.

Fig. 2 is a sectional view of the base portion of the design shown in Figure 1, on the line 2—2.

The characteristic feature of my invention resides in the specific standard and supporting arm in association with the lamp and base as shown.

I claim:

The ornamental design for a sun lamp, substantially as shown and described.

PAUL N. CLOUTIER.
